UNITED STATES PATENT OFFICE.

PHILIP T. DODGE, OF BROOKLYN, NEW YORK, ASSIGNOR TO MERGEN-
THALER LINOTYPE COMPANY, A CORPORATION OF NEW YORK.

LINOTYPE-MACHINE.

SPECIFICATION forming part of Letters Patent No. 792,973, dated June 20, 1905.

Application filed January 25, 1905. Serial No. 242,588.

To all whom it may concern:

Be it known that I, PHILIP T. DODGE, of Brooklyn, county of Kings, and State of New York, have invented a new and useful Improvement 5 in Linotype-Machines, of which the following is a specification.

My invention has reference to linotype-machines and kindred machines wherein printing bars or slugs are cast in a slotted mold 10 against a composed line of matrices temporarily seated against the face of the mold, the mold and matrices being thereafter separated and the slug or cast thereafter ejected from the mold. In the operation of this class of machines it is found that the slugs will sometimes 15 adhere tenaciously to the mold, so that their ejection is difficult. This is particularly the case when the machine is operated at high speed and the slug ejected before there has been sufficient time for it to cool and contract or when the slug is provided with transverse 20 ribs, so that its longitudinal contraction causes these ribs to bind strongly in the mold.

The aim of my invention is to overcome this 25 difficulty by slightly opening the mold automatically to relieve the slug from pressure, so that it may be more readily ejected.

My invention is applicable in all machines in which the slotted mold retains its form and 30 demands the ejection of the slug edgewise. This class of molds is to be distinguished from the molds in which the parts are widely separated after each casting action to permit the delivery of the type or slug.

I have shown my invention in the form 35 more particularly adapted for application to the well-known Mergenthaler linotype-machine of the general organization represented in Letters Patent of the United States No. 55,000.

The drawings are limited to those parts immediately associated with my improvement. All other parts may be of the usual or of any other suitable construction.

Figure 1 is a plan view showing the mold-carrying wheel, mold, ejector, and trimming-knives, the mold being shown in the ejecting position and in section on the line 1-1 of Fig. 2 at a point above the slot or casting-cham-

ber. Fig. 2 is a front view of the parts shown 50 in the preceding figure. Fig. 3 is a vertical section through the mold and adjacent parts in the casting position, the section being taken on the line 3-3 of Fig. 4. Fig. 4 is a vertical section on the line 4-4 of Figs. 1 and 2. Fig. 55 5 is a perspective view of one of the wedges for opening the mold. Fig. 6 is an elevation of the mold having my invention embodied therein in modified form.

Referring to the drawings, A represents 60 the vertical intermittently-rotated mold-carrying wheel or disk; B, the mold secured therein; C, the mouth of the melting-pot, serving to close the back of the mold when in the casting position and to deliver molten metal 65 thereto.

D represents the composed line of matrices, serving to temporarily close the face of the mold and to form the letters or characters on the edge of the slug cast therein. 70

E is the first "elevator," so called, in which the line of matrices D and spacers F is suspended and presented first to the mold and thereafter to the distributing mechanism.

G is a horizontally-reciprocating ejector- 75 blade arranged to be projected through the mold after the latter has been turned from the casting position for the purpose of ejecting the slug or linotype I at the front.

H is a horizontally-reciprocating frame serv- 80 ing as a guide for the ejector-blade and also as a support for the axis of the mold-wheel, permitting the wheel to be moved forward and backward.

J and J' are two parallel knives located on 85 the frame forward of the ejector for the purpose of trimming the side faces of the slug or linotype as it is expelled from the mold.

The foregoing parts may all be constructed and arranged to operate in the ordinary manner with the exception hereinafter noted.

The composed line of matrices and spacers after being delivered to the elevator E is lowered thereby to a position in front of the mold, as shown in Fig. 3. The mold-wheel is 95 moved forward until the face of the mold is closed tightly against the matrices, and at the same time the mouth of the pot is moved for-

ward to close tightly against the back of the mold. The molten metal is then delivered from the pot into the mold, producing a slug or linotype having on its edge the characters formed by the matrices. The pot then retreats from the mold, the mold moves rearward to withdraw the characters on the slug from the matrices, and the wheel is turned through three-fourths of a revolution, carrying the mold from its original horizontal position at the top to the vertical position, as shown in Figs. 1, 2, and 4, with the contained slug or linotype in a vertical position opposite the ejector-blade. The mold-wheel and mold are again moved forward until the front face of the mold stands close to the knives J J', after which the ejector-blade advances, expelling the slug from the mold and driving it between the knives into the galley at the front, all of these actions being the same as in the ordinary machine.

I will now describe my improvement. The mold consists, as shown in United States Letters Patent to Rogers, No. 620,804, of a lower or body portion b , screwed firmly and permanently to the wheel, an overlying cap portion b' , and intermediate liners or spacing-pieces b^2 and b^3 , which determine the length and height of the slot or mold proper, b^4 , and of the slug or linotype produced therein. Heretofore this mold-cap has been fastened down firmly in place and was not moved except when released by the operator for the purpose of substituting liners of different length or thickness to change the dimensions of the cell and of the slugs produced. Instead of fixing this cap rigidly in place I hold it normally down in its operative position by means of springs M, seated on its outer ends and confined by nuts m , mounted on the upper ends of screw-rods m' , which are extended down through the cap and seated firmly in the body of the mold. These springs are of such strength that the cap is held down with pressure sufficient to keep it and the underlying liners in operative position. If desired, additional locking devices may be provided for the liners to prevent them from slipping out of position. In each end of the mold-body, beneath the cap and liners or directly beneath the cap, if preferred, which latter arrangement is shown in Fig. 6, I mount a transverse wedge n of slight taper and with their thicker ends at the front, so that when pushed rearward from their normal position, as shown in Fig. 4, they will serve to slightly raise the mold-cap, and thereby relieve the contained slug from pressure and friction while being ejected. These wedges may be actuated in any suitable manner; but I recommend as the most simple means two fixed studs or pins T, mounted on one of the trimming-knives or on an adjacent fixed portion of the frame in position to act upon the forward ends of the wedges and drive them rearward as the mold is carried forward toward the knives prior to

the ejection of the slug, as before referred to. This action of the wedges is plainly shown in Figs. 1 and 4. The rear ends of the wedges, which are preferably enlarged to prevent their accidental escape, are located in such position that when the mold is turned in its casting position the mouth of the advancing pot will act on the rear ends of the wedges and drive them forward, thus permitting the cap to assume its original and operative position. The rear ends of the wedges will stand flush with the rear face of the mold, so that they will not interfere with the trimming of the base of the slug by the usual stationary knife employed for the purpose. The elevation of the cap required is exceedingly slight. Under ordinary circumstances a rise of a thousandth of an inch will be quite sufficient.

It will be observed that the mold as herein shown is self-contained—that is to say, its parts are so constructed and united that they are not dependent upon the mold-disk or other external parts to keep them in operative relation. The mold as a whole may be applied and removed at will without fitting or adjusting its parts or changing their relations to one another.

The essence of the invention lies in combining with a mold the parts of which remain always in approximately operative position means for separating the parts or relieving them from confinement to an extent just sufficient to relieve the friction on the contained slug.

It is obvious that the wedges may be made in various forms, applied in various positions, and operated by various devices without changing essentially their mode of action, and it is also obvious that springs of any other form may be employed to hold the cap and that the wedges may be replaced by any other devices which will serve as their mechanical equivalents.

As before stated, the wedges may be mounted directly beneath the cap b' of the mold, as shown in Fig. 6, instead of under the liners, as illustrated in the other figures. The function and mode of operation of the wedges would be the same in both cases, except that in the construction of Fig. 6 the operation of the wedges to open the mold will lift the cap only, while their operation when beneath the liners will lift both the cap and the liners.

I am aware that a mold having its opposing members provided with cores or projections to form cavities in the slug has been provided with springs tending to open the mold and with external mechanisms for effecting its closure, as shown in Patent No. 637,117, the mold being opened in each case a distance equal to the thickness of the slug for the purpose of releasing the latter. It will be observed in my structure the springs tend to close the mold and that the wedges serve to positively open the same to an extent just suf-

ficient to relieve the pressure and friction on the slug.

Having described my invention, what I claim is—

5 1. A linotype-mold consisting of a body portion, a cap portion, connections permitting the cap a lifting motion only in relation to the body, spring connections tending to hold the parts in operative relation, and cap-lifting devices seated in and forming a permanent portion of the mold.

10 2. In a linotype-machine, a slotted self-contained mold, comprising the body and cap, springs tending to hold said parts in operative relation, and intermediate movable wedges to effect the lifting of the cap.

15 3. In a linotype-mold, the combination of the body portion, the removable liners, the cap, spring connections tending to depress the cap, and transverse movable wedges *n.*

20 4. In a linotype-machine, a mold comprising a body portion, a rising-and-falling top, and means for effecting the movements of the top, in combination with means for moving the 25 mold between the casting and the ejecting points, for also moving the mold forward edgewise of the slug at the ejecting-point, and means actuated by such movement for operating the cap-adjusting devices while the mold 30 is at the ejecting-point.

5. In a linotype-machine, the mold-carrying wheel, having a rotary movement and a movement in an axial direction, in combination with the slotted mold having a cap adapted to rise and fall, wedges to lift the cap, 35 springs to depress the same, wedge-acting devices to effect the lifting of the cap when the mold is at the ejecting position, and the melting-pot arranged to move the wedges in the reverse direction for lowering the cap at the 40 casting position.

6. In a linotype-machine and in combination with the mold provided with a rising-and-falling top, spring connections to depress the top, and a wedge mechanism arranged to lift 45 the top when the mold is in the ejecting position.

7. In a linotype-machine, trimming-knives *J*, *J'*, and the movable mold provided with a rising-and-falling cap and with springs and 50 wedges for adjusting the cap, in combination with fixed devices *T*, to actuate the wedges.

In testimony whereof I hereunto set my hand, this 24th day of January, 1905, in the presence of two attesting witnesses.

PHILIP T. DODGE.
